Liam Broton
WITNESS:

BY *Victor J. Evans*

ATTORNEY

UNITED STATES PATENT OFFICE.

FRANK H. MCENANEY, OF BROOKLYN, NEW YORK.

DENTIFRICE RECEPTACLE.

Application filed March 26, 1924. Serial No. 702,114.

To all whom it may concern:

Be it known that I, FRANK H. MCENANEY, a citizen of the United States, residing at Brooklyn, in the county of Kings and State of New York, have invented new and useful Improvements in Dentifrice Receptacles, of which the following is a specification.

This invention relates to a dentifrice receptacle.

The principal object of the invention is to provide a compact and neat toilet article which may be carried in the pocket or a traveling bag, and which is capable of instant use as the tooth brush and the dentifrice are enclosed in a single container.

A further object of the invention is to provide a means of dispensing the dentifrice upon the bristles of the tooth brush, without removing the dentifrice tube from the container.

A further object of the invention is to construct an article of the class mentioned which is simple in construction, cheap of manufacture and highly sanitary for the purpose intended.

With these and other objects in view, the invention resides in certain novel construction and combination and arrangement of parts, the essential features of which are hereinafter fully described, are particularly pointed out in the appended claims, and are illustrated in the accompanying drawing, in which:

Figure 1 is a perspective view of the invention with the parts enclosed.

Figure 2 is a vertical longitudinal sectional view therethrough.

Figure 3 is a transverse sectional view on the line 3—3 of Figure 2.

Figure 4 is a sectional elevation showing the position of the tooth brush ready for use.

Referring more particularly to the drawing, the reference numeral 10 designates a receptacle or casing which is opened at both ends and which is provided with a partition 11 intermediate its ends whereby to form a pair of compartments 12 and 13. The open end of the compartment 12 is provided with a socket 14, and adjacent the socket 14 is an internally screw-threaded portion 15. A tooth brush 17 is normally housed in the compartment 12 and comprises a bristle section 18 and a handle section 19. The bristle section 18 and the handle section 19 are detachably connected together in any suit-

able manner but in the present instance the means is shown as comprising a set screw 20, whereby a new bristle section may be associated with the head when desired. 60 The handle section 19 is formed with a screw threaded portion 21 for co-action with the threads 15 of the casing when the same is in normal position as shown in Figure 2. Adjacent the screw threaded portion 21 65 there is provided a smooth portion 22 for co-action with socket 14 when the tooth brush is in position for use such as shown in Figure 4 and in which case the casing serves as a handle. The end of the handle 19 is formed with a manipulating portion 23 whereby the brush may be screwed into the casing or removed therefrom as will be readily understood.

Insertible in the compartment 13 is a dentifrice tube 24 of the collapsible type, and the same is retained therein by a cap 25 detachably connected to the open end of the compartment. A presser member 26 made of a flexible material such as fiber, rests upon 80 the entire length of the tube 24, and the side edges of the member are beaded as at 27 for co-action in the inner wall of the compartment. The member 26 is adapted to be brought into pressing engagement with 85 the tube and for this purpose I employ a lever 28, which is fulcrumed to the casing as at 29, and is provided with a head 30 which projects through a slot 31 in the casing and into the compartment 13. A 90 pin 32 passes through the head and into longitudinal grooves 33 formed on the member 26 whereby the presser member may be removed from the compartment when desired. The head 30 of the lever is formed with a 95 rounded face 34 for co-action with the top of the presser member and it will be seen that upon the raising of the lever 28 to a position shown in dotted lines in Figure 2, that the presser member will move in a 100 downward direction to impart an even pressure over the entire surface of the tube. This downward movement will cause the beaded edges 27 to co-act with the inner walls of the compartment to hug the tube 105 and to assist in the complete ejection of the contents therefrom.

From the foregoing description, it will be manifest that the tooth brush is removed from its compartment and the cap removed 110 from the dentifrice compartment, after which the bristle section of the brush is

placed beneath the open end of the tube and the lever 28 given an upward pull whereby to compress and eject a sufficient amount of paste upon the bristle of the brush, after which the brush section is inserted in the socket as shown in Figure 4 and is then ready for use.

While I have described what I deem to be the most desirable embodiment of my invention, it is obvious that many of the details may be varied without in any way departing from the spirit of my invention and I therefore do not limit myself to the exact details of construction herein set forth nor to anything less than the whole of my invention limited only by the appended claims.

What is claimed as new is:—

1. An article of the class mentioned including a receptacle open at one end, a dentifrice tube adapted to be inserted in said receptacle, a yieldable presser member over-

lying the entire length of the tube and co-acting with the inside walls of said receptacle and operable means for moving said presser member into pressing engagement with said tube, said means comprising a lever fulcrumed to said receptacle and having a head engaging said presser member.

2. A device of the class described including a tubular housing, a collapsible tube removably mounted in said housing, a yieldable presser member within said housing and extending approximately the length of said tube, portions formed on said member for engagement with the inside walls of said housing, and a lever fulcrumed to said housing for co-action with said presser member to cause said portions to partially surround the tube to eject the contents therefrom.

In testimony whereof I have affixed my signature.

FRANK H. McENANEY.
